(57) **CLAIM**

The ornamental design for a toy with parts having multiple positions, as shown and described.

DESCRIPTION

FIG. 1 is a front left perspective view showing my new design of a toy with parts having multiple positions with the ears of design in an open position;

FIG. 2 is a front elevational view thereof, with the ears of the design in the open position;

FIG. 3 is a front elevational view thereof, with the ears of the design in an intermediate position;

FIG. 4 is a front elevational view thereof, with the ears of the design in a closed position;

FIG. 5 is a top plan view thereof, with the ears of the design in the open position;

FIG. 6 is a top plan view thereof, with the ears of the design in the intermediate position;

FIG. 7 is a top plan view thereof, with the ears of the design in the closed position;

FIG. 8 is a rear elevational view thereof, with the ears of the design in the open position;

FIG. 9 is a rear elevational view thereof, with the ears of the design in the intermediate position;

FIG. 10 is a rear elevational view thereof, with the ears of the design in the closed position;

FIG. 11 is a right side elevational view thereof, with the ears of the design in the open position;

FIG. 12 is a right side elevational view thereof, with the ears of the design in the intermediate position;

FIG. 13 is a right side elevational view thereof, with the ears of the design in the closed position;

FIG. 14 is a left side elevational view thereof, with the ears of the design in the open position;

FIG. 15 is a left side elevational view thereof, with the ears of the design in the intermediate position;

FIG. 16 is a left side elevational view thereof, with the ears of the design in the closed position;

FIG. 17 is a bottom plan view thereof, with the ears of the design in the open position;

FIG. 18 is a bottom plan view thereof, with the ears of the design in the intermediate position; and,

FIG. 19 is a bottom plan view thereof, with the ears of the design in the closed position.

(Continued)

The broken lines the figures are for the purposes of illustrating environment of the toy with parts having multiple positions only and form no part of the claimed design.
